UNITED STATES PATENT OFFICE.

GEORGE HORRALD DILLON, OF SAWTELLE, CALIFORNIA, ASSIGNOR OF ONE-HALF TO
JOHN H. DOBBINGS, OF SOLDIERS HOME, CALIFORNIA.

ANCHORING DEVICE.

1,244,432.

Specification of Letters Patent. Patented Oct. 23, 1917.

Application filed March 1, 1915. Serial No. 11,374.

To all whom it may concern:

Be it known that I, GEORGE H. DILLON, a citizen of the United States, residing at Sawtelle, in the county of Los Angeles and 5 State of California, have invented a new and useful Anchoring Device, of which the following is a specification.

This invention is specially adapted for anchoring railway rails to wooden ties but 10 is applicable to other uses where a spike or the like is employed for detachably fastening parts together.

An object of the invention is to provide means whereby a railway rail or other body 15 may be detachably fastened to a railway tie or other support in such a manner as to avoid any accidental release of the anchoring device by vibrations or by shrinkage of the wood or other material into which the 20 spike is driven.

An object of the invention is to use as a part of the anchoring device a common railway spike of the kind now in use and to absolutely secure said spike against accidental loosening or withdrawal and yet to 25 make provision whereby the spike can be released and withdrawn and can again be inserted, driven home and secured as firmly as before.

30 The invention includes an anchor attachment to be used in connection with the common railway spike or the like and also includes said anchor attachment and a specific releasable lock for connecting said anchor attachment with the spike.

An object of the invention is to provide means which reinforce the spike to secure a railway rail to a railway tie.

Other objects are cheapness, simplicity of 40 construction, ease of application, ease of release, and avoidance of destructive action upon the body to which the anchoring device is applied.

The accompanying drawings illustrate the 45 invention.

Figure 1 is a fragmental perspective view of the reinforced anchor device in anchoring position to secure a railway rail to a railway tie. Fragments of the rail, rail- 50 plate and tie are also shown, the lower portion of said tie being broken away to expose the embedded portion of the anchor.

Fig. 2 is a side elevation of parts shown in Fig. 1 after the spike has been driven and 55 withdrawn and the anchor attachment

placed in position in the hole thus formed and a spike in position ready to be driven home preparatory to being fastened as in Fig. 1.

Fig. 3 is a sectional view analogous to 60 Fig. 2 showing the spike driven home and secured.

Fig. 4 is an elevation of the anchor attachment detached and viewed from the left of Fig. 3, the locking means being shown 65 extended above the anchor attachment for clearness of illustration.

Fig. 5 is a fragmental view illustrating a modified form in which the device may be embodied.

The anchor attachment consists of limb 1 having at one end a sharp bend forming a detent 2 and at the other end a knuckle 3 through which extends a pivot 4 pivotally securing an anchor link 5 to said anchor attachment. Said link may be of any suitable construction, either solid metal or in the form of a U-shaped strap that may or may not be provided with a cover portion 5', said link being perforated to receive the 80 pivot 4 and also perforated a distance from said pivot to receive a pin 6, which pivots a latch 7 to the link 5. Said latch may conveniently be made of two links such as are used in the construction of an ordinary 85 sprocket chain, said links being pivoted to opposite sides of the anchor link and provided at their free ends with perforations 8 through which a key 9 may be inserted.

The knuckle 3 overhangs upon the detent 90 side of the limb 1 to thus form a channel b in which the key 9 is adapted to seat to latch the links 5 and 7 down in place.

The spike is of the usual construction having a bevel point 10 and straight body 95 11, and a head extension 12 to extend over the flange 13 of the railway rail.

In order to apply the anchor, the spike or the like is first driven into the tie 15 to make a suitable hole 16 and is then withdrawn. Then the anchor attachment limb 1 is inserted into the hole to a depth which will bring the knuckle 3 just above the level of the spike head when it is driven home onto the flange of the rail. This is gaged 100 by making the detent of the same width as the spike body and the anchor of a length equal to the combined length of the spike and head above the bevel point 10 of the spike, so that after the spike has been driven 110

to the depth to which it is designed to be seated in order to hold the rail flange and then withdrawn and the anchor attachment limb 1 inserted, said limb will automatically adjust itself to the right depth by coming to rest on the converging walls of the hole.

Positive gage means to limit the depth to which the anchor may drop in the hole 16 10 may be provided in the form of a suitable shoulder 14 on the limb 1, near the top thereof and upon the same side as the overhanging knuckle 3. This shoulder is adapted to engage the edge of the spike aperture 15 a in the tie plate 13 and support the anchor in proper position when the same is dropped into the hole.

The anchor will be placed in position with the detent projecting away from the 20 rail. Then the spike will be inserted between the limb 1 and the rail and driven home, the head extension of the spike being directed away from the anchor attachment or piece. When the spike is thus driven 25 home alongside of said limb with the head extension on the top of the flange the detent 2 is projected laterally into the tie near the bottom of the hole, see Fig. 3, after which the anchor link 5 is swung over onto 30 the head of the spike and the latch swung down into position below the overhanging knuckle 3, and the key 9 is then inserted through the holes 8 in the ends of the latch and underneath the overhanging knuckle 35 thereby locking the anchor to the spike.

Said key may be of any suitable construction and may be an ordinary wire nail driven through and bent to prevent accidental withdrawal.

40 In the modification shown in Fig. 5, the key 9 is assembled in place between the latch links 7 and is provided with a bent handle portion 17 by which to turn said key and a locking lip 18 while the latch links 7 45 are made sufficiently long to swing over the overhanging knuckle 3 when said lip is turned outwardly, as indicated by dot and dash lines Fig. 5. After swinging the latch down into position the key may be turned 50 to throw the lip under the overhanging knuckle and thereby lock the anchor and spike together.

It is understood that the hole to receive the detent may be made by any other suitable means instead of the spike.

When it is desired to detach the anchor device the bent key of Figs. 1 to 4 will be straightened and driven out, the latch raised and the spike thus released is then pulled in 60 the usual way. The anchor piece or limb 1 may then be detached by inserting the spike to wedge it from the side of the spike hole, thus withdrawing the detent from such wall.

Since the detent is formed as a sharp 65 lateral bend formed at the lower end of the

anchor, the insertion of the spike to wedge loose the anchor is easily effected and likewise the driving of the detent into the tie is effected in a practical way when the spike is driven down from the position shown in 70 Fig. 2.

In the form shown in Fig. 5 the key will be rotated to release it and will then be withdrawn thus releasing the spike as before.

I claim:

1. An anchoring device comprising an anchor piece provided with a detent at its lower end and adapted to be inserted into the hole formed by a spike or the like before the spike is driven alongside of the anchor piece; means pivoted at the upper end of the anchor piece and adapted to swing above the anchor piece for locking the anchor piece and the spike together; and means for locking the pivoted means above the spike.

2. An anchoring device comprising a limb adapted to be inserted into a hole formed by a spike or the like before the spike is driven alongside of the limb; a bend forming a detent at the lower end of the limb and adapted to project laterally into the wall of the hole as the spike is driven alongside of the limb; a releasable lock pivotally connected with the limb at the upper end thereof and adapted to swing above the limb for locking the limb to the spike; and means for locking the releasable lock above the spike.

3. An anchoring device comprising a limb adapted to enter a hole formed by a spike or the like, a detent at the lower end of said limb adapted to project laterally into the wall of the hole as the spike is driven 105 alongside of the limb, and an anchor link at the upper end of the limb adapted to extend over onto the spike head and a latch to lock said limb, link and spike together.

4. An anchoring device comprising a limb adapted to enter a hole formed by a spike or the like, a detent at the lower end of said limb adapted to project laterally into the wall of the hole as the spike is driven 110 alongside of said limb, an anchor link at the upper end of the limb adapted to swing over onto the spike-head, and means to lock said link in place over the spike-head to thereby secure said spike against accidental loosening.

5. An anchoring device comprising a limb adapted to enter a hole formed by a spike or the like, a detent at the lower end of said limb adapted to project laterally into the wall of the hole as the spike is driven 115 alongside of said limb, and an anchor link at the upper end of the limb adapted to swing over onto the spike-head, a latch to secure said link in place over the spike-head, and a releasable key for said latch.

6. An anchoring device comprising an anchor limb provided with a detent at its lower end and adapted to enter the hole formed by a spike, the detent projecting laterally into the wall of the hole as the spike is driven alongside of said anchor, an overhanging knuckle at the upper end of the anchor limb, an anchor link pivoted to said overhanging knuckle and adapted to extend over the spike-head, a latch for said link and a pin for the latch adapted to engage with the overhanging knuckle to thereby lock the link in place over the spike-head.
- 15 7. An anchoring device comprising an anchor piece provided with a detent at its lower end and adapted to enter the hole formed by a spike, the detent projecting laterally into the wall of the hole as the spike is driven alongside of said anchor piece, an overhanging knuckle at the upper end of the anchor piece, an anchor link pivoted to said overhanging knuckle and adapted to extend over the spike-head, a latch comprising a link at each side of said anchor link and arranged to swing down into position below said overhanging knuckle, and a key to pass through the latch links and underneath the overhanging knuckle to lock said anchor link in place over the spike-head and thereby anchor the spike.
- 25 8. An anchoring device comprising a limb

adapted to enter a hole formed by a spike or the like, a detent at the lower end of said limb adapted to project laterally into the 35 wall of the hole as the spike is driven alongside of said limb, an anchor link at the upper end of the limb adapted to swing over onto the spike-head to lock the limb and spike together, and gage means to limit 40 the depth to which the limb may drop in the hole to thus position said anchor link preparatory to swinging over said spike-head.

9. An anchoring device comprising a limb adapted to enter a hole formed by a spike or the like, a detent at the lower end of said limb adapted to project laterally into the wall of the hole as the spike is driven alongside of said limb, an anchor link at the 50 upper end of the limb adapted to swing over onto the spike-head to lock the limb and spike together, and a shoulder on the limb near the top thereof adapted to engage the edge of the hole and thereby support the 55 limb and link in position preparatory to swinging said link over the spike-head.

In testimony whereof, I have hereunto set my hand at Los Angeles, California, this 20th day of February, 1915.

GEORGE HORRALD DILLON.
